UNITED STATES PATENT OFFICE.

WILLIAM H. SMITH, OF CLEVELAND, OHIO.

FAUCET.

1,218,962.

Specification of Letters Patent. Patented Mar. 13, 1917.

Application filed April 22, 1913. Serial No. 762,910.

To all whom it may concern:

Be it known that I, WILLIAM H. SMITH, a citizen of the United States, residing at Cleveland, in the county of Cuyahoga and 5 State of Ohio, have invented a certain new and useful Improvement in Faucets, of which the following is a full, clear, and exact description, reference being had to the accompanying drawings.

10 This invention relates to valves or faucets of a type especially adapted for use with tank wagons which contain gasoline, oil, or other such liquids; and among its objects are the provision of a simple means of protection 15 for the stem of the valve or faucet whereby it is secured against being tampered with or turned except by the employment of a wrench designed particularly for the purpose; the provision of such a relation between the valve aperture and the thread 20 pitch as to facilitate the operation of the valve; the provision of a valve construction whereby splashing of liquid from a pail or container hung thereon is greatly reduced. 25 While further objects and advantages will appear as the description proceeds.

In the drawings, Figure 1 represents a plan and Fig. 2 a central vertical section of my improved valve or faucet, like reference characters being used in the two views 30 to designate corresponding parts.

Carried by the tank 1 is a connection 2 (both being indicated by dot-and-dash lines in the drawing), upon the outer end of 35 which is adapted to be screwed the internally threaded boss 3 which projects rearwardly from the globular valve casing 4. The outer surface of the boss 3 is provided with a plurality of flat faces, as indicated 40 at 3^a, for the application of a wrench, whereby the faucet may be screwed onto the connection 2. Projecting downwardly, and inclined slightly forwardly from the vertical center of the valve casing, is a spout 5 which 45 is externally threaded for the application of a cap or hose connection (neither of which is shown). A horn or projection 6 extends from the front of the valve casing diametrically opposite the boss 3 and provides a supply 50 port for a pail, when such is being filled from the faucet. The location of the horn 6 forward of the discharge spout renders the latter eccentric to the pail hung on the

horn, but the inclination of the spout directs the liquid toward the center of the pail thus 55 preventing the spashing and loss of liquid frequently occasioned with prior devices.

An annular flange 7 projects upwardly from the globular valve casing 4 and is internally threaded for the reception of the 60 lower threaded end of the cap 8. The lower central portion of the cap 8 is provided with a bore having a square, fast thread cut therein, preferably of a double or triple pitch, and adapted to operate within this bore is 65 a correspondingly threaded portion of the shank 10 of the spigot 11, the lower end of which terminates in a circular plug 12. To the underneath face of the plug 12 is secured a pliable washer 13, of any suitable material, by a nut 14 which is adapted to be threaded on the stud 15, depending from 70 said plug. Located in the lower portion of the valve casing 4 and concentric with the vertical axis of the spigot 11 is an annular 75 valve seat 16 with which is adapted to co-operate the washer 13 when the valve is closed. The upper end of the shank of the spigot is reduced to provide a stem 17 which is squared at 18. The upper central portion 80 of the cap 8, which is occupied by the stem 17, is recessed to provide a packing gland for said stem within which packing-material 19 is retained and squeezed about said stem by a gland nut 20 which is adapted to be 85 threaded into the upper end of the aforesaid recess.

The gland nut 20 is provided with a circular cavity 21 of a depth slightly greater than the height of the squared portion 18 of 90 the stem 17 which projects thereinto through a hole in the nut. When the valve is closed, the upper end of the stem projects but a little more than half way through the cavity 21, and when it is fully open it is still below the plane of the upper surface of the nut 20. Also the length of the threaded portion of the stem is less than that of the threaded portion of the casing so that the stem threads may not enter the packing 100 gland when the valve is opened. To operate the valve, I provide a wrench 22 (which is indicated by dot-and-dash lines in the drawing) having a circular head 23 of slightly less diameter than the cavity 21 and 105 of substantially the same vertical dimen-

sion and which is provided with a central, squared socket for the reception of the squared portion 18 of the stem 17. While I have described this portion of the stem 17 as square, it is obvious that it may be made of any desired cross-sectional shape, the socket in the wrench, in any event, being made of a corresponding shape.

The connection 2 is preferably very short so as to bring the faucet as near the tank as possible and the length of the faucet is also decreased as much as possible so as to render the same as safe from accidental breakage as may be. The mobile nature of refined oils particularly of gasoline necessitates the very tight closing of the faucet to prevent leakage. Frequently this tight closing is effected by using a screw of small pitch but this is objectionable since it causes a considerable loss of time in opening the valve. If a thread of steeper pitch be employed, the force necessary to the tight closing of the valve can be achieved only by the use of a handle of considerable length, and the angular movement of this handle is limited by the wall of the tank since the length of the handle is greater than the distance between the stem and the tank. Accordingly I have found that the most satisfactory results are obtained by balancing the pitch of the thread against the diameter of the outlet passageway, in such wise that the movement of the handle through 180° shall effect the complete opening of the valve.

If r represents the radius of the opening in the valve seat, and A the area we know that

$$A = \pi r^2$$

This amount of opening becomes effective when the area of the annular passageway between the face of the valve and that of the seat is equal to the area of the seat opening, i. e. $\therefore$

$A^1 = 2\pi rh$
in which h represents the height to which the valve is raised.

$$A^1 = 1$$

$$Hr^2 = 2\pi rh$$

$$h = \frac{1}{2}r$$

Copies of this patent may be obtained for five cents each, by addressing the "Commissioner of Patents, Washington, D. C."

But if P represents the pitch of the thread,

$$P = 2h$$

since the handle is to be restricted to a half turn. Therefore

55

$$P = r$$

which indicates that the pitch should equal the radius of the valve seat opening.

Obviously the actual possible movement of the handle is somewhat more than 180° in case the valve be adjusted properly but this is substantially the maximum permissible movement owing to the constant change in adjustment due to wear and compression of the washer 13. Inasmuch as a pitch of this steepness affords a considerable amount of room between successive convolutions of the same thread, a multiple thread is preferably employed to fill this space and steady the valve.

Obviously the exact proportions herein given may be varied within reasonable limits without sacrificing the advantages in view, wherefore I do not propose to restrict myself to the exact details shown or described.

Having thus described my invention, what I claim is:

In a tank faucet a casing having a threaded boss for attachment to a horizontal tank nipple, and a forwardly and downwardly inclined discharge spout, a circular seat at the juncture of the casing and spout, a neck integral with said casing and opposite said seat, a bonnet connected to said neck having a recess in its upper end, a valve adapted to rest upon said seat, the stem of said valve working in said bonnet and recess, packing in said recess, and a recessed nut for securing said packing in place, the end of the valve stem extending into the recess of said nut.

In testimony whereof, I hereunto affix my signature in the presence of two witnesses. 95

WILLIAM H. SMITH.
